SLIPPER OR SIMILAR ARTICLE

Anne Yandell, New York, N. Y.

Application December 1, 1949, Serial No. 6,366

Term of patent 7 years

(Cl. D7—7)

To all whom it may concern:

Be it known that I, Anne Yandell, a citizen of the United States of America, residing in the city of New York, county of New York, State of New York, have invented a new, original, and ornamental Design for a Slipper or Similar Article, of which the following is a specification, reference being had to the accompanying drawings, forming a part thereof, wherein:

Fig. 1 is a side elevational view of a slipper or similar article, showing my new design; and

Fig. 2 is a perspective view with the straps partially draped in the position in which they would appear when in use.

I claim:

The ornamental design for a slipper or similar article, substantially as shown and described.

ANNE YANDELL.
